COAXIAL TRANSMISSION LINE TERMINATION

Owen Orlando Fiet, Oaklyn, N. J., assignor to
**Radio Corporation of America, a corporation
of Delaware.**

Application September 7, 1949, Serial No. 114,400

6 Claims. (Cl. 333—97)

1

The invention relates to coaxial transmission lines and it particularly pertains to an improved arrangement for terminating open-ended coaxial transmission line sections.

Open-ended coaxial transmission lines are very frequently employed in high frequency radio installations as impedance matching devices, resonant circuit elements, notch filters, and the like, to great advantage. While theoretically the known arrangements are equally applicable to high power installations as well as low power installations, it has been found that in installations of 10 kw. and higher power, the differential thermal expansion between the inner and outer conductors of an open-ended coaxial transmission line has a detrimental effect on the tuning of the line.

It is an object of the invention to provide a terminating arrangement for an open-ended coaxial transmission line which will not be affected by temperature variations.

It is another object of the invention to provide a termination for an open-ended coaxial transmission line eliminating the deleterious effects caused by differential thermal expansion between the inner and outer conductors of the line.

It is a further object of the invention to provide a simple and inexpensive termination for a coaxial transmission line which is readily adjustable and completely reliable in operation.

These and other objects of the invention which will appear as the specification progresses are attained by means of a device consisting essentially of a conductive sleeve placed over the end of the inner conductor of an open-ended coaxial transmission line, which sleeve is restrained by the outer conductor only, and means are provided to maintain electrical contact between the inner conductor and the sleeve, meanwhile permitting the inner conductor to move within the sleeve in accordance with temperature variations whereby the effect of differential thermal expansion between the inner and outer conductors is eliminated.

The invention will be described with reference to the accompanying drawing forming a part of the specification and in which:

Fig. 1 is an illustration, partly in cross-section, of an embodiment of the invention; and

Fig. 2 is an illustration of an alternate embodiment of the invention.

Referring to Fig. 1, there is shown an end portion of a coaxial transmission line 11 having a sheath conductor 13 and a concentrically arranged inner conductor 15 rigidly held in place by means of a plurality of insulator members 17.

2

preferably but not necessarily in the form of annular plugs which are held in place either by crimping the sheath conductor as shown at 19, by pins as shown at 21, or any other method known to those skilled in the art. In prior art arrangements, the end of conductor 15 is allowed to ride in the aperture of insulator 17 where the expansion and contraction of inner conductor 15 due to temperature variations, being different from that of the sheath conductor, would introduce deleterious effects on the tuning of the circuit in which the coaxial transmission line section is employed.

According to the invention, these disadvantages are eliminated by providing a conductive sleeve 23 which is restrained from movement in the axial direction by insulating member 17 and sheath conductor 13. In the preferred arrangement, insulator 17 and sleeve 23 are fastened together by slightly undercutting sleeve 23 for a portion intermediate its ends which is just sufficiently long enough to accommodate the thickness of insulator 17 which is forced over the remainder of sleeve 23. Sleeve 23, which may be 25 a tubular member or which may be entirely closed at one end as is shown, has an annular groove 27 milled in the inner wall thereof to accept a toroidal coil spring 29 through the aperture of which inner conductor 15 of coaxial transmission line 11 slides to provide electrical connection to 30 sleeve 23 suitable for the low current flow which is encountered near the end of an open circuit transmission line. Preferably, annular groove 27 is of sufficient depth that only a slight portion of coil spring 29 protrudes into bore 25 of sleeve 35 23, in order to retain the coil spring prior to the insertion of inner conductor 15 into bore 25 and also to maintain the overall dimension of sleeve 23 at a minimum. While the arrangement shown 40 may be located within the sheath by calculation, it is anticipated that the arrangement will be preferably inserted into the transmission line, and its location determined experimentally prior to fastening insulator 17 to sheath conductor 13 of the coaxial transmission line. In order to 45 facilitate such adjustment, holes 39 may be bored into sleeve 23 transversely of the axis thereof to accommodate some form of tool, such as a tong-like spanner, which may be used to slide the assembly comprising insulator 17 and sleeve 23 50 in the axial direction in order to determine the optimum location of the sleeve.

Since it will be obvious that the tuning of such a transmission line is somewhat critical, the adjustment of the device may be more readily

and accurately made with the arrangement shown in Fig. 2, wherein a plurality of slots 31 are milled into sheath conductor 13 of transmission line 11 in a direction diagonally to the axis thereof and insulating member 17 is held in place by means of studs 33 passing through slots 31. For clarity, the inner conductor 15, sleeve 23 and coil spring 29 are omitted from Fig. 2. Plate members 35 made of suitable resilient material are placed over studs 33 to serve both as coverings for slots 31 and also as lock washers for acorn nuts 36. The arrangement is tuned by loosening nuts 36 and exerting force to rotate member 17 about the axis of transmission line 11, which rotation will cause studs 33 to bear against the sides of slots 31 and force member 17 to move in the axial direction. Once the tuning of the coaxial line section has been determined, nuts 36 are tightened and the transmission line will remain properly tuned despite temperature variations. The ratio of axial to rotational movement is varied by varying the angle at which slots 31 are milled, the optimum angle being that which will provide the desired range of tuning with the maximum rotation allowable under the particular circumstances.

While the invention has been described in terms of express embodiments, it is to be understood that obvious modifications thereof will be suggested to those skilled in the art without departing from the spirit and scope of the invention.

I claim:

1. A coaxial transmission line section incorporating means to adjust the length thereof without deleterious effect thereto by reason of relative thermal expansion of the inner and sheath conductors of said line section, the sheath conductor of said line section having elongated slots arranged therein diagonally of the axis of said sheath conductor, a sleeve member surrounding the inner conductor of said line section, an insulating member fixed to said sleeve member, guide members fixed to said insulating member and arranged in the slots in said sheath conductor to cause said insulating member and said sleeve member to move axially in response to rotation thereof initially to adjust the length of said transmission line section, and a coil spring interposed between said sleeve member and said inner conductor to provide electrical contact therebetween without restraining relative movement in the axial direction therebetween to maintain the length of said transmission line section substantially constant as initially adjusted.

2. An open-ended coaxial transmission line section incorporating means to adjust the length thereof without deleterious effect thereto by reason of relative thermal expansion of the inner and sheath conductors of said line section, the sheath conductor of said line section having elongated slots arranged therein diagonally of the axis of said sheath conductor, a sleeve member surrounding the inner conductor of said line section and having an annular groove in the inner wall thereof, an insulating member fixed to said sleeve member, stud members fixed to said insulating member and arranged in the slots in said sheath conductor to cause said insulating member and said sleeve member to move axially in response to rotation thereof initially to adjust the length of said transmission line section, and a coil spring arranged in the annular groove of said sleeve member to provide electrical contact between said sleeve member and said inner conductor without restraining relative movement

in the axial direction therebetween to maintain the length of said transmission line section substantially constant as initially adjusted.

3. An open-ended coaxial transmission line section incorporating means to adjust the length thereof without deleterious effect thereto by reason of relative thermal expansion of the inner and sheath conductors of said line section, the sheath conductor of said line section having elongated slots arranged therein diagonally of the axis of said sheath conductor, a sleeve member surrounding the inner conductor of said line section and having an annular groove in the inner wall thereof, an insulating member fixed to said sleeve member, stud members fixed to said insulating member and arranged in the slots in said sheath conductor to cause said insulating member and said sleeve member to move axially in response to rotation thereof initially to adjust the length of said transmission line section, locking means arranged on said stud members to fix the position of said sleeve with respect to said sheath conductor, and a coil spring arranged in the annular groove of said sleeve member to provide electrical contact between said sleeve member and said inner conductor without restraining relative movement in the axial direction therebetween to maintain the length of said transmission line section substantially constant as initially adjusted.

4. A terminating device for a coaxial transmission line having an inner conductor and a sheath conductor, the sheath conductor of said coaxial transmission line having elongated slots arranged therein diagonally of the axis of said sheath conductor, including a sleeve member surrounding the inner conductor of said line, an electrically spacing member fixed to said sleeve member to space the same from said sheath conductor, guide members fixed to said electrically spacing member and arranged in the slots in said sheath conductor to cause said spacing member and said sleeve member to move axially in response to rotation thereof initially to adjust the length of said coaxial transmission line, and a resilient element interposed between said sleeve member and said inner conductor to provide electrical contact therebetween without restraining relative movement in the axial direction therebetween to maintain the length of said transmission line substantially constant as initially adjusted.

5. A terminating device for a coaxial transmission line having a conductive inner member and a sheath conductor, the sheath conductor of said coaxial transmission line having elongated slots arranged therein diagonally of the axis of said sheath conductor, including a sleeve member surrounding the conductive inner member of said coaxial transmission line, one of said members having an annular groove in a wall thereof, an insulating member fixed to said sleeve member, stud members fixed to said insulating member and arranged in the slots in said sheath conductor to cause said insulating member and said sleeve member to move axially in response to rotation thereof initially to adjust the length of said coaxial transmission line, and a resilient element arranged in said annular groove to provide electrical contact between said sleeve member and said conductive inner member without restraining relative movement in the axial direction therebetween to maintain the length of said transmission line section substantially constant as initially adjusted.

6. A terminating device for an open-ended coaxial transmission line having a conductive inner member and a sheath conductor, the sheath conductor of said transmission line having elongated slots arranged therein diagonally of the axis of said sheath conductor, including a sleeve member surrounding the conductive inner member of said coaxial transmission line, one of said members having an annular groove in a contiguous wall thereof, an insulating member fixed to said sleeve member, stud members fixed to said insulating member and arranged in the slots in said sheath conductor to cause said insulating member and said sleeve member to move axially in response to rotation thereof initially to adjust the length of said coaxial transmission line, and locking means arranged on said stud members to fix the position of said sleeve with respect to said sheath conductor, and a resilient element arranged in the annular groove of said one member to provide electrical contact between said sleeve

member and said inner conductor without restraining relative movement in the axial direction therebetween to maintain the length of said transmission line substantially constant as initially adjusted.
